(57) **CLAIM**

The ornamental design for a laptop computer carrier, as shown and described.

DESCRIPTION

FIG. 1 is a front perspective view of the laptop computer carrier in closed position with handle pulled slightly outward in use and with a laptop computer shown in phantom therein; FIG. 2 is a front outer view of the laptop computer carrier open and with handle in non-use position.

FIG. 3 is a left side elevation view thereof, the right side elevation view being a mirror image thereof.

FIG. 4 is a rear, inner elevation view thereof.

FIG. 5 is an upper plan view thereof; and,

FIG. 6 is a lower plan view thereof.

The broken lines in FIG. 1 are directed to environment only and form no part of the claimed design. The cross hatching shown in FIGS. 1 and 4 represents a pattern or texture—but no particular pattern or texture—different from that on the reverse side of the laptop computer carrier. This pattern or texture is part of the claimed design.
